UNITED STATES PATENT OFFICE.

GEORGE T. PEARSONS, OF NEW YORK, N. Y.

FIRE-EXTINGUISHER.

1,191,991.

Specification of Letters Patent. Patented July 25, 1916.

Application filed February 5, 1916. Serial No. 76,244.

To all whom it may concern:

Be it known that I, GEORGE T. PEARSONS, a citizen of the United States, residing in the borough of Manhattan, city, county, and 5 State of New York, have invented new and useful Improvements in Fire-Extinguishers, of which the following is a specification.

This invention relates to syringes in which pumping mechanism is provided in a cylinder or reservoir to create an air pressure in the reservoir and such air pressure utilized to eject a liquid contained in the reservoir, and it is the object of the invention to provide improved means to obtain this result 10 which are simple and cheap in construction and efficient in operation, and which are adapted for fire extinguishers.

A further object of the invention is to provide means in a syringe of this type 20 whereby the outlet of the reservoir is at all times connected with the liquid in the lower-most part of the reservoir no matter in what position the outlet of the syringe may be.

Another object of the invention is to provide means to close the outlet of the reservoir 25 to prevent leakage therethrough when the syringe is not in use, and to permit of the creating of an air pressure in the reservoir by the pumping mechanism previous to the 30 discharging of the contents of the reservoir by said air pressure.

In the drawing accompanying and forming a part of this specification there is illustrated in sectional side elevation a 35 syringe with an embodiment of my invention applied thereto.

In the embodiment of my invention shown in the drawing I provide a tank or reservoir for a fire extinguishing liquid, said reservoir 40 consisting of a body portion 2, preferably cylindrical in shape, and the ends 3 and 4 secured thereto as by soldering or otherwise, the end 3 having a discharge outlet 5 in coaxial alinement with the axis of the reservoir, and a filler opening closed by a plug 6. The end 3 is preferably dished as shown to permit of the standing of the 45 syringe upon a horizontal surface, although means may be provided to suspend the 50 syringe from a hook or the like.

Mounted in the reservoir at one side of the longitudinal axis and adjacent the side is a piston chamber consisting of the cylinder 7 having a driving fit in a bore in heads 8 and 55 9 in the cylinder, the head or end 9 abutting against the reservoir end 4, and the bore

therein being of the same diameter as the inside of the cylinder 7 and extending through said head 9 and registering with an opening in the reservoir end 4 of the same 60 diameter. The outer end of the bore is internally screw threaded for the engagement of a flanged perforated nut 10. The engagement of the nut in said head 9 clamps the reservoir end between the flange of the nut 65 and the head 9 thereby securing the piston chamber to said end 4 and supporting it therefrom. The piston cylinder 7 with its connected heads is of less length than the length of the reservoir. Each of the heads 70 8 and 9 has a recess 11 in the lateral wall communicating with the piston chamber when the heads are secured thereto, and said recesses are adapted to register with openings in the body portion 2 of the reservoir. 75 These recesses 11 have internal screw threads for the reception of perforated flanged plugs or caps 12 and 12' from the exterior of the reservoir, the inner ends of said plugs being constructed to constitute seats for balls 13, 80 normally retained in said seats to close the openings or perforations in the plugs by springs 14. The valve plugs also serve to support the piston chamber in the reservoir. 85

Air is drawn alternately through the openings in the plugs to opposite ends of the piston chamber by a piston 14, having suitable packing, reciprocable in the piston chamber by a rod 15 extending through the opening in the nut 10 and a stuffing box 16 90 carried by said nut to the exterior of the piston chamber and reservoir, and has an operating handle 17 fixed to the outer end.

To eject the air which is alternately drawn into opposite ends of the piston chamber 95 into the reservoir, I provide a tube 18 connected at one end to the rod 15, as at 19, said tube slidably engaging in and at all times extending through an opening in the end 8 of the piston chamber and a stuffing 100 box 20 carried by said end. The end of the tube adjacent to where it is connected to the rod 15 has spaced apart lateral ports 21 and 22, the piston being mounted upon said tube to have a limited to and fro movement thereon between abutments to control the opening and closing of the ports, one of which abutments consists of a shoulder 23 formed by the connection of the tube with the rod 15 and the other a collar 23' fixed to the tube. 110 The end of the tube 19 extending into the reservoir has an inward closing and outward

opening spring check valve 24, the outer diameter of said valve being the same as the diameter of the tube. By this construction it will be obvious that upon removal of the 5 nut 10 the piston with the tube 18 may be readily removed from the piston chamber for the substitution of parts or otherwise and replaced.

During the initial outward movement of 10 the piston rod 15 the said rod with the tube 18 will have a limited movement independent of the piston until the latter engages with the abutment 23' thereby uncovering the ports 22 and covering the ports 21 when 15 the piston will move with the rod drawing the air into the piston chamber through the opening in the plug 12 in front of the piston. During the initial inward movement of the piston rod and tube they will have a slight 20 movement independent of the piston until the latter engages with the abutment 23, the piston thereby uncovering the ports 21 and closing the ports 22. During this inward movement of the piston air will be drawn 25 into the piston chamber through the port in plug 12', and the air previously drawn into the piston chamber in front of the piston will be ejected through the ports 21 and tube 18 into the reservoir, the pressure of such 30 air readily unseating the valve 24, and upon the next outward movement of the piston the air in the tube in the piston will be ejected through the ports 22 into the reservoir, and the foregoing described operation will 35 continue so long as the piston is reciprocated.

To at all times connect the outlet 5 of the reservoir with the liquid in the lowermost part of the reservoir no matter in what position the said outlet may be, I fix a tube 25 at 40 one end in said outlet, said tube extending through an opening in a projection of the end 8 of the piston chamber and into a bore 26 in a projecting portion of the other end 9 of the piston chamber so that the inner end 45 of the tube will lie adjacent the reservoir end 4. The bore 26 registers with an opening in said end 4 and is closed by a flanged plug or nut 27, thus providing a chamber 50 with which the end of the tube 25 is in communication. A tube 28 of somewhat greater diameter than the outlet tube 25, and through which the latter passes, is rotatably supported at one end in a stuffing box 29 in the end 8 of the piston chamber, and the other 55 end in a stuffing box 30 in the opposite end 9 of the piston chamber; said stuffing box 30 and the tube 28 serving to close the end of the bore opposite the plug 27 so that such bore will constitute an entirely closed chamber 60 with which the ends of the tubes 25 and 28 are in communication. By this construction the tube 28 is adapted to swing around the tube 25 as an axis and the axis of the reservoir. Connected to the tube 28 by a 65 lateral branch tube or pipe 31 is a pipe or

tube 32, said tube 32 extending longitudinally of and with its ends adjacent the ends and sides of the reservoir. The ends of the tube 32 are constructed to constitute seats for balls 33 carried by cages, in the form of caps 34, connected to the ends of the tube with the outer ends closed, said closed outer ends serving as supports for the ball when unseated. To permit entrance of the liquid through said cages to the tube they have lateral ports 35, the cages being so proportioned that when the ball is unseated these ports will be slightly above the ball to prevent any possibility of the balls being forced to their seats by pressure inserted thereon by liquid entering through the ports 35. It will be obvious that should the discharge end of the reservoir be tilted down from the horizontal that the ball at the then upper end of the tube will be automatically seated 85 closing said end of the tube and the ball at the then lower end of the reservoir will drop away from the seat and will be so supported as to prevent the liquid from entering through the ports 35 in the ball carrying cage to force said ball to its seat.

To prevent leakage of liquid that may enter through tubes 32 and 31 into the chamber 26 through the outlet tube 25 when the syringe is not in use, and to permit of the 95 creating of an air pressure in the reservoir by the pumping mechanism to be utilized for the discharge of the liquid from the reservoir, I provide a valve 37 having a stem 38 passing through the plug 27 to open and 100 close the valve from the exterior of the reservoir. This stem passes through a stuffing box carried by the plug 27 and has screw-threaded connection with the latter, and the valve is manipulated by a finger piece 105 40 fixed to the other end of the stem. The end of the tube 25 preferably has a member 39 to constitute a seat for the valve 37.

In operation the valve 37 being closed the 110 pumping mechanism is actuated to create air pressure in the reservoir. When this air pressure is sufficient pumping ceases and the valve 37 is opened by the finger piece 40 when the pressure of the air will cause the 115 liquid in the reservoir to pass through one of the ends of the intake tube 32, depending upon the position in which the syringe is held, and through pipes 32, 31, and 28 to the chamber 26 and from said chamber through 120 the outlet tube 25.

Variations may be resorted to within the scope of my invention.

Having thus described my invention I claim:

1. In a syringe, the combination with a reservoir having an outlet, of a piston chamber in said reservoir having intakes from the exterior of the reservoir; a piston reciprocable in said chamber; a tube reciprocable 130

- with the piston and slidably engaging in one end of the piston chamber within the reservoir to connect the piston chamber with the reservoir, said tube having ports within the piston chamber the opening and closing of which ports is controlled by the piston during the reciprocation thereof to alternately connect the tube through the ports with the piston chamber at opposite sides 70 of the piston, substantially as and for the purpose specified.
2. In a syringe, the combination with a reservoir having an outlet, a cylinder therein having air intakes at opposite ends from the exterior of the reservoir; a piston to reciprocate in the cylinder; a tube reciprocable with the piston and slidably in one end of the cylinder within the reservoir to connect the cylinder with the reservoir; and a 75 rod to reciprocate the piston and tube from the end of the cylinder opposite to the tube, and said piston during the reciprocation thereof alternately connecting the inner end of the tube to the cylinder at opposite sides 80 of the piston, substantially as and for the purpose specified.
3. In a syringe, the combination with a reservoir having an outlet, of a cylinder therein having air intakes at its ends from the exterior of the reservoir and having an outlet in one end; a tube slidably engaging in the cylinder outlet and having ports adjacent the end within the cylinder; a piston reciprocable in the cylinder mounted on 85 said tube to control the opening and closing of the tube ports and alternately connect the tube with the cylinder at opposite sides of the piston; and means extending to the exterior of the cylinder and reservoir opposite 90 site to the tube to reciprocate the piston and tube, substantially as and for the purpose specified.
4. In a syringe, the combination of a reservoir having an outlet; a cylinder having suction air intakes at its ends from the exterior of the reservoir and having an opening in one end; a tube slidably in the opening in the cylinder end to connect the cylinder with the reservoir and having spaced 95 apart ports at the end within the cylinder; a piston reciprocable in the cylinder slidably mounted on said tube to draw air into the cylinder and to control the opening and closing of the tube ports to alternately connect the tube to the cylinder at opposite ends of the piston; and a rod to reciprocate the piston and tube extending exterior of the cylinder and reservoir opposite to the tube. 100
5. In a syringe, the combination of a reservoir having an outlet; a cylinder therein having air suction inlets adjacent its ends from the exterior of the reservoir and an opening in one end into the reservoir; a tube slidably in the cylinder opening to connect the cylinder with the reservoir and having a 105 series of spaced apart lateral ports at the end within the cylinder; abutments at opposite sides of the ports; a piston on the tube to have movement between the abutments to control the opening and closing of the ports; and a rod extending from the end of the cylinder and reservoir opposite to the tube to reciprocate the piston and tube and cause the piston to cover and uncover the tube ports to alternately connect the tube 110 with the cylinder at opposite ends of the piston, substantially as and for the purpose specified.
6. In a syringe, the combination of a reservoir having an outlet; a cylinder therein having air suction inlets at its ends from the exterior of the reservoir; a tube reciprocable in a cylinder end within the reservoir to connect the cylinder with the reservoir, the inner end of said tube having spaced apart lateral ports and an outwardly opening and inwardly closing valve at the opposite end; a piston reciprocable in the cylinder with the tube and having a limited to and fro movement on the tube to control the opening 115 and closing of the ports to alternately connect said tube with the cylinder at opposite sides of the piston; and a rod extending to the exterior of the cylinder and reservoir opposite the outlet to reciprocate the piston and tube, substantially as and for the purpose specified. 120
7. A syringe comprising a reservoir having a discharge outlet; a cylinder having air suction inlets; a piston reciprocable in the cylinder; a tube reciprocable with the piston and at all times communicating at one end with the reservoir and having ports controlled by the piston to alternately connect the tube with the cylinder at opposite 125 ends of the piston during the reciprocation thereof; and a handle exterior of the cylinder opposite to the discharge outlet to reciprocate the piston. 130
8. In a syringe, the combination of a cylinder having a discharge outlet in one end coaxial with the cylinder; a piston chamber in said cylinder having air suction inlets from the exterior of the cylinder adjacent opposite ends and an air outlet leading into the cylinder; piston mechanism to draw air into the piston chamber through the air inlets and eject it into the cylinder through the air outlet; and an intake to the cylinder outlet to swing on an axis centrally of the cylinder, substantially as and for the purpose specified.
9. In a syringe, the combination of a cylinder having an outlet in one end coaxial with the cylinder; a piston chamber in said cylinder located at one side of the axis of the cylinder having air suction inlets from the exterior of the cylinder adjacent opposite ends and an air outlet into the cylinder; piston mechanism to draw air into the cylinder; 135

- ton chamber through the air inlets and eject it into the cylinder; and intakes to the cylinder outlet comprising a tube extending longitudinally of the cylinder with its ends lying adjacent the sides and at opposite ends of the cylinder and adapted to oscillate on an axis in line with the cylinder outlet and parallel with the piston chamber, substantially as and for the purpose specified.
- 5 10. In a syringe, the combination of a cylinder having an outlet at one end coaxial with the cylinder; a piston chamber in said cylinder located at one side of the axis of the cylinder having air suction inlets from the exterior of the cylinder adjacent opposite ends and an outlet into the cylinder; piston mechanism to draw air into the piston chamber through the air inlets and eject it into the cylinder; a discharge tube fixed 20 at one end in the cylinder outlet and extending into the cylinder to a point adjacent the opposite end of the cylinder; and an intake to said discharge tube comprising a tube extending longitudinally of the cylinder with its ends lying adjacent the sides and opposite ends of the cylinder and connected to the discharge tube to swing around said tube, substantially as and for the purpose specified.
- 15 25. 11. In a syringe, the combination of a cylinder having an outlet at one end in line with the axis of the cylinder; a piston chamber in said cylinder located at one side of the axis of the cylinder having air suction inlets adjacent opposite ends and an outlet into the cylinder; piston mechanism to draw air into the piston chamber through the air inlets and eject it into the cylinder; a tube fixed at one end in the cylinder outlet and 30 extending into the cylinder to a point adjacent the opposite end of the cylinder; and intakes to said tube comprising a tube extending longitudinally of the cylinder with its ends lying adjacent the sides and at opposite ends of the cylinder and connected to the discharge tube to swing around said tube, substantially as and for the purpose specified.
- 35 40. 12. In a syringe, the combination of a cylinder having an outlet at one end coaxial with the cylinder; a piston chamber in said cylinder located at one side of the axis of the cylinder having air suction inlets and an outlet into the cylinder; piston mechanism to draw air into the piston chamber through the air inlets and eject it into the cylinder; a tube fixed at one end in the cylinder outlet and 45 extending into the cylinder to a point adjacent the opposite end of the cylinder; and intakes to said tube comprising a tube extending longitudinally of the cylinder with its ends lying adjacent the sides and at opposite ends of the cylinder and having means to connect said tube to the first tube and support the same to oscillate around the first tube as an axis, substantially as and for the purpose specified.
- 50 55. 13. In a syringe, the combination of a cylinder having an outlet at one end coaxial with the cylinder; a piston chamber in said cylinder located at one side of the axis of the cylinder having air suction inlets and an outlet into the cylinder; piston mechanism to draw air into the piston chamber through the air inlets and eject it into the cylinder; a tube fixed at one end in the cylinder outlet and 60 extending into the cylinder to a point adjacent the opposite end of the cylinder; an intake tube to said first tube to swing around said tube as an axis; and a valve operable from the exterior of the cylinder to engage with the end of said first tube extending into the cylinder to close the same, substantially as and for the purpose specified.
- 65 70. 14. In a syringe, the combination of a cylinder having an outlet at one end coaxial with the cylinder; a piston chamber in said cylinder located at one side of the axis of the cylinder having suction inlets and an outlet into the cylinder; piston mechanism to draw air into the piston chamber through the air inlets and eject it into the cylinder; a tube fixed at one end in the cylinder outlet; said tube extending through a projection on one end of the piston chamber and into a bore in a projection of the other end of the piston chamber; a tube through 75 which the first tube extends rotatably supported in the projections on the ends of the piston chamber and connected to the outlet tube through the bore in the projection on the outer end of the piston chamber; a laterally projecting branch tube connected to said latter tube; and a tube connected to the branch tube extending longitudinally of the cylinder with its ends lying adjacent the sides and at opposite ends of the cylinder; and inwardly closing and outwardly opening valves for the ends of said latter tube, substantially as and for the purpose specified.
- 80 85. 15. In a syringe, the combination of a reservoir for a liquid having a discharge outlet; a piston chamber in said reservoir; a piston to reciprocate in the piston chamber; valved air inlets to the piston chamber on opposite sides of the piston from the exterior of the reservoir; a tube slidably mounted in one end of the piston chamber and reciprocable with the piston, said tube having ports in the end within the piston chamber, the opening and closing of which ports are controlled by the piston to connect said tube with the piston chamber at opposite sides of the piston during the reciprocation of the piston; a spring influenced valve carried at the end of the tube within the reservoir, said valve opening outward from and closing into the tube; and means to reciprocate the pistons and tube, substantially as and for the purpose specified.
- 90 95. 16. In a syringe, the combination of a reservoir to contain a liquid having a discharge outlet; a piston chamber in said reservoir; a piston to reciprocate in the piston chamber; suction air inlets to the piston chamber on opposite sides of the piston from the exterior of the reservoir; and air outlet means from the piston chamber to the reservoir to discharge the air drawn into the piston chamber on opposite sides of the piston into the reservoir during the reciprocation of the piston substantially as and for the purpose specified.
- 100 105. 17. In a syringe, the combination with a reservoir for a liquid having a discharge outlet, of a pump comprising a piston, a

cylinder in the reservoir in which the piston is arranged to reciprocate and divided by said piston into two compartments, suction air inlets from the exterior of the reservoir to each of said compartments, and air outlet means common to both of said compartments to discharge the air drawn into the compartments from said compartments into the reservoir during the reciprocation of the piston, substantially as and for the purpose specified.

17. In a syringe, the combination with a cylinder to contain a liquid having a discharge outlet in one end coaxial with the cylinder, of a piston chamber in said cylinder; a piston to reciprocate in the piston chamber; suction air inlets to the piston chamber on opposite sides of the piston from the exterior of the cylinder; air outlet means 15 from the piston chamber to the cylinder to discharge the air drawn into the piston chamber on opposite sides of the piston into the cylinder during the reciprocation of the piston; and an intake tube extending longitudinally of the cylinder with its ends adjacent the side and opposite ends of the cylinder connected to the outlet of the cylinder substantially as and for the purpose specified.

20

25

18. In a syringe, the combination with a cylinder to contain a liquid having a discharge outlet in one end coaxial with the

cylinder, of a piston chamber in said cylinder; a piston to reciprocate in the piston chamber; suction air inlets to the piston chamber on opposite sides of the piston from the exterior of the cylinder; air outlet means from the piston chamber to the cylinder to discharge the air drawn into the piston chamber on opposite sides of the piston into the cylinder during the reciprocation of the piston; said piston chamber and piston being located adjacent the wall of the cylinder; and a tube connected to the outlet of the cylinder extending parallel with the piston chamber with its ends adjacent the side of the cylinder opposite the piston chamber and at opposite ends of the cylinder, substantially as and for the purpose specified. 35 40 45

19. In a syringe, the combination with a reservoir to contain a liquid having an outlet, of a piston chamber in said reservoir, a piston to reciprocate in said chamber, a suction air inlet from the exterior of the reservoir to the piston chamber on opposite sides of the piston; air outlet means from the piston chamber to the reservoir; and an intake tube extending longitudinally of the reservoir with its ends adjacent the side and opposite ends of the reservoir connected to the outlet of the reservoir to oscillate on an axis centrally of the reservoir, substantially as and for the purpose specified. 50 55 60
